UNITED STATES PATENT OFFICE.

NILS H. ANDERSON, OF MIDDLETOWN, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

PAPER-HOLDER FOR TYPE-WRITERS.

1,164,623.

Specification of Letters Patent. Patented Dec. 21, 1915.

Application filed April 9, 1910. Serial No. 554,405.

To all whom it may concern:

Be it known that I, NILS H. ANDERSON, a citizen of the United States, residing at Middletown, in the county of Middlesex 5 and State of Connecticut, have invented certain new and useful Improvements in Paper-Holders for Type-Writers, of which the following is a full, clear, and exact description, such as will enable others skilled 10 in the art to which it appertains to make and use the same.

The present invention relates to the alining scale of typewriting machines, and has for its object to provide a combined alining 15 scale, printing point indicator and card-holding device, of simple and practical construction, indicating at all positions of the platen the exact printing point upon the paper, permitting the operator to write to 20 the extreme bottom or top edge if desired, yet which will be of few parts, simple and easy to manufacture and assemble.

In the accompanying drawings, wherein are shown one of many possible embodiments of my invention, Figure 1 is a plan view of a part of the typewriting machine sufficient to illustrate one embodiment of the 25 present invention; Fig. 2 is a side elevation of the same; and Fig. 3 is a detail front 30 view of the alining scale and its mountings.

Similar reference characters refer to similar parts throughout the drawings.

While the present invention is illustrated and described with reference to that form of 35 machine known as the "Noiseless" typewriting machine, it is to be understood that this invention may be applied to other forms of typewriting machines.

Referring now to the drawings in detail, 1 40 represents a shiftable platen carriage on which is mounted a revoluble platen roller 2 and a relatively stationary flat platen 3 over which the paper passes and with which the type carriers (not shown) co-act. The 45 carriage 1 reciprocates on a shift rail 4 movable in opposite directions from a normal intermediate position for the purpose of printing upper or lower case characters. Centrally disposed and rigidly connected 50 with this shift rail 4 is a projecting part or support 5 which by means of trunnions 6 supports a bearing plate for the upper end of a telescopically constructed escapement

shaft 7. This shaft 7 is provided with a pinion 8 meshing with a rack 9 mounted on the lower part of the carriage 1. On the support 5 are forwardly projecting ears or lugs 10 having vertical slots 10' therein through which pass trunnions 11 supporting a rock shaft 12 on which are loosely mounted two connected arms 13 provided at their upper parts with laterally extending wings or scale portions 14 having an intermediate cut-away portion 15 indicating the printing point. The slots 10' permit a vertical adjustment of the scale and the cut-away portion 15 allows the type carriers to move freely forward into engagement with the paper over the platen 3. A spring 16 is spirally wound around the shaft 12 and rigidly connected at one end to a relatively fixed part and at its other end to one arm 13; it normally urges the arms and scale carried thereby into engagement with the flat platen 3, as clearly shown in Fig. 2.

The spring 16 has sufficient tension to hold the arms 13 and scale portions carried thereby in close contact with the platen, or to hold the paper or card closely adjacent the printing point. As the flat platen 3 is stationary with relation to the carriage at all times, and with the scale except when the carriage is being spaced, the scale may press it with considerable force, so that the paper is held firmly in place, allowing the operator 85 to write at the very bottom or top of the sheet. In this manner the scale acts as a paper clip or card holding device, and being shiftable with the platen will allow the operator to print upper and lower case type 90 without fear of the paper slipping from between the card holder and the platen. Should it be attempted to use a scale of this construction yieldingly held in contact with an ordinary platen roller, there would be a 95 tendency of the scale to cut into the paper or roller when the same was rotated in the reverse direction.

The trunnions 11 supporting the shaft 12 upon which the printing point indicator is 100 mounted, comprise threaded pins passing through the ears 10 provided with lock-nuts 17 and 18 upon the opposite sides thereof. It is thus seen that by loosening these lock-nuts the threaded pins or trunnions may be 105 moved in opposite directions laterally to

adjust the scale relatively to the printing point, and they may also be moved vertically in the slots 10' to adjust the same vertically, after which when the scale is in adjusted position the lock-nuts 17 and 18 may be tightened to hold the scale firmly in adjusted position.

5 Mounted in the upper part of the supporting block 5 are ribbon guides 19 which are bent outwardly and upwardly, carrying at the upper part thereof suitable holding means 20 for the ribbon, whereby the same is held in position to be engaged by the type carriers and moved therewith to the impression point.

10 The manner of use and operation of this device is as follows: The paper is inserted beneath the platen roller 2 and over the flat platen 3, forcing the holder or indicator 14' 20 away against the yielding action of the springs 16. The upper edge enables the operator to determine the line position while the intermediate cut-away portion 15 between the laterally extending arms 14 will 25 denote the exact point of impression of the next character to be printed. When the carriage is shifted by means (not shown) applied to the ends of the rail 4 in any suitable manner, the support 5 is carried thereby 30 by with the upper part of the telescopically constructed escapement shaft 7 so that the scale and ribbon guides all move together to indicate to the operator the point of impression.

35 As the wings 14 bear with considerable pressure against the platen, it is to be noted that a plurality of sheets of paper may be fed around the roller and held against the platen with sufficient force to enable printing to be effected, even at the very bottom 40 of the sheet, while if a card is inserted it will be held against the printing point in all positions and may conform to the curve of the platen roller with the aid of the usual feed 45 rollers and clips, not herein shown.

It is thus seen that this invention provides for a simple and practical device adapted to accomplish, among others, the objects set forth, in which the alining scale 50 is always held in contact with the paper about the platen to indicate the alinement and also the exact printing point at which the next character is to be printed, whether the carriage is shifted for upper or lower 55 case characters. The scale being held normally in yielding contact with the platen, any reasonable number of sheets of paper may be inserted, thereby increasing its efficiency and allowing the operator to write at 60 any portion of the sheets. Being yieldingly held in this manner, the scale acts as a satisfactory clip or card holder allowing the operator to write on paper of any quality or size.

As many changes could be made in the 65 above construction and many apparently widely different embodiments of this invention could be made without departing from the scope thereof, it is intended that all matter contained in the above description or 70 shown in the accompanying drawings shall be interpreted as illustrative and not in a limiting sense.

Having described my invention, what I claim as new and desire to secure by Letters 75 Patent, is:—

1. In a typewriting machine, in combination, a shiftable platen carriage, a flat platen secured between the end plates thereof, a shift rail vertically disposed beneath the 80 central longitudinal dimension of the carriage and along which the carriage is adapted to travel, said shift rail having a forwardly projecting part, and a vertically disposed alining scale mounted on the forward 85 portion of said part adapted normally to bear against and indicate the printing point upon said flat platen.

2. In a typewriting machine, in combination, a reciprocating carriage, a flat platen carried thereby, a shiftable support for said carriage, and means mounted on said support adapted to hold a paper in coactive relation with said flat platen in all positions thereof.

95 3. In a typewriting machine, in combination, a reciprocating carriage, a flat platen carried thereby, a shift rail on which said carriage is adapted to travel, a projection on said rail, and vertically adjustable indicating means pivotally mounted on said projection adapted to indicate the printing point on said flat platen.

100 4. In a typewriting machine, in combination, a reciprocating carriage, a flat platen carried thereby, a single shift rail beneath and on which said carriage is adapted to travel, a projection on said rail, and paper holding means pivotally mounted on said projection adapted to engage said platen.

105 5. In a typewriting machine, in combination, a reciprocating carriage, a relatively stationary flat platen carried thereby, a shift rail along which said carriage is adapted to travel, a projection from said shift rail, a 110 paper holding device pivotally mounted on said projection, and spring means adapted to urge said pivoted device into engagement with the platen.

115 6. In a typewriting machine, in combination, a reciprocating shiftable carriage, a platen carried thereby, an alining scale, a support for said alining scale, trunnions on said support in which said alining scale is mounted, means adapted to permit a lateral 120 and a vertical adjustment of said scale, and means adapted to hold said alining scale normally in contact with said platen.

7. In a typewriting machine, in combination, a reciprocating flat platen, a support relatively to which said flat platen is adapted to reciprocate, an alining scale mounted on
5 said support held in yielding engagement with said flat platen, and means adapted to permit an adjustment of said scale laterally.

In testimony whereof I affix my signature, in the presence of two witnesses.

NILS H. ANDERSON.
